HERMAN MERKEL, OF EAST ORANGE, AND JACOB BUECHER, OF NEWARK, NEW JERSEY; SAID BUECHER ASSIGNOR TO SAID MERKEL.

FASTENING DEVICE FOR WOODEN BOXES AND THE LIKE.

1,410,210.

Specification of Letters Patent. Patented Mar. 21, 1922.

Application filed September 11, 1920. Serial No. 409,617.

To all whom it may concern:

Be it known that we, HERMAN MERKEL and JACOB BUECHER, citizens of the United States, and residents of East Orange, county of Essex, and State of New Jersey, and Newark, county of Essex, and State of New Jersey, respectively, have invented certain new and useful Improvements in Fastening Devices for Wooden Boxes and the like, of which the following is a specification.

This invention relates to an improved fastening device mainly employed for holding parts of wooden boxes and the like together so that the parts can not be separated except by mutilating the box at that point, and such devices are largely used to prevent theft from boxes in transportation.

The invention relates to a clip including spaced perforated plates, and particularly to a particular form of nail which, after being driven through the wood of the box and through the perforations in the plates, can not be withdrawn.

The invention is illustrated in the accompanying drawing, in which Figure 1 is a section showing part of the side wall and the cover of a box with the fastening device in position. Figure 2 is a section on line 2—2 in Figure 1. Figure 3 is a top view of a clip used in the device, and Figure 4 is a section similar to Figure 2, but showing no part of the box and illustrating the nail in several positions it assumes by being driven into position.

In the drawing we will assume that 10 is the side wall of a wooden box and 11 is the lid, although it will be evident that this clip can be used in all parts, on the bottom, sides and top, where these elements are joined. The first step is to drive into position, usually by means of a hammer, a pair of perforated plates which for convenience I join together by a lip so as to form a clip. In the form shown the clip consists of the lip 12 which is bent at its ends to form the perforated plates 13 and 14, which are usually joined, as at 15, to facilitate their entrance into the wood, and when it is desired to use a lighter weight of metal the proper stiffness can be contributed by providing these plates with corrugations 16.

Perforations 17 and 18 are placed in the plates 13 and 14, respectively, these per-

forations being adapted to receive a nail. The clip is driven so that one of its plates enters one of the elements, such as the side 10, and the other plate enters the other element, such as the cover 11, thus assisting in holding them together.

The nail, to hold the clip in position and to prevent its withdrawal, must, in order to guard the device against unauthorized removal, be permanently fastened, and the nail described herein is insured, when once driven into position, against withdrawal through the perforations and the clip can not be removed unless the material of the box is broken apart at that point. This prevents the removal of any part of the contents of the box and prevents the depredation very often common in transportation where furs and similar expensive articles are withdrawn from packing boxes and the like by a slight raising of the lid, and after a part of the contents is removed the lid again hammered shut, so that there is no detection of the loss until the boxes are unpacked at their destination.

The nail that we provide is usually made of flat material, the shank 19 of the nail being usually provided with a head 20 and being further provided with teeth on its opposite edges, these teeth being disposed so that the tapered edges between the teeth engage the side edges of the perforations 17 and 18 and cause the nail to take different angular or tilted positions successively as the nail is driven through the perforations in the plates, and if there is any attempt to withdraw the nail after it is in position the teeth engage the side edges of these perforations and the nail can not be pulled out.

The teeth are preferably made in pairs, the illustration showing two pairs or series, an upper series and a lower series, the teeth 21 and 22 comprising the upper series, and the teeth 23 and 24 comprising the lower series. The end of the nail is pointed usually with a pronounced taper, as at 25, and when it is driven down through the cover 11 and enters the perforation 17 it fits tightly; in fact the width of the nail at the point where the tooth 24 is situated can be slightly in excess of the diameter of the opening 17, but in this case it will slightly upset the edge of the perforation and pass through, but since the teeth 23 and 24, in 110

fact the teeth of both series, are separated by a space slightly in excess of the width of the material of which the plates 13 and 14 are made, the tapered edge 26 forces the nail laterally as the tooth 24 has cleared the plate 13, and this lateral motion causes a slight tilting of the nail until the tooth 23 has passed through the perforation 17. The tapered edge 27 between the teeth 24 and 22 now causes the nail to be tilted in the other direction, as is shown in Figure 4 in dotted outline, until the tooth 21 has passed through the perforation 17, and by this time the point 25 has entered the perforation 18. The tapered edge 28 now engages the edge of the perforation 17 and the tooth 21 is moved laterally as the nail is driven so that it is underneath the edge of the plate 13, and after the tooth 22 has cleared the perforation 17, the tapered edge 27, bearing against the edge of the perforation 18, with the tapered edges 28 and 29 entering the perforation 17, straightens up the nail, and when it is driven down until the head is flush with the top of the box the nail assumes the position shown in Figure 2.

When the nail is moved upward in an attempt to withdraw it from this position by a tool seated under the head 20, the teeth will engage the bottom edges of the plates 13 and 14 and it is impossible to withdraw the nail back through these perforations, and if the nail is tilted in one direction to clear one of the teeth the inclination of the nail will cause a tooth on the opposite side thereof to engage one of the plates. Of course the successive inclinations of the nail are at but slight angles, and since it is guided by the inclined faces passing through the perforations no care is necessary in driving the nail into position.

We prefer to make the top of the head 20 rounded, as at 30, and in Figure 2 the showing is rather conventional since the material 31, by a few blows of the hammer when the nail is being seated, forces the soft wood of which these boxes are made so that it is pressed inward and over the head of the nail. This eliminates any chance of there being sharp projections to injure the hands of workmen handling the box.

It will be noted that the upper and lower series of teeth are separated by a distance approximately the same as the distance be-

tween the plates, and we find by making the upper tooth 23 of the lower series and the lower tooth 21 of the upper series on the same side of the nail, that the disposition of the teeth is such as to bring about the best results to prevent withdrawal. 60

It will be evident that slight changes can be made in the shape of the parts without departing from the scope of our invention. 65

We claim:

1. A fastening device for wooden boxes and the like, said device including spaced plates with aligned perforations, and a nail having its edges formed with teeth spaced 70 in a manner to cause the said edges to engage the edges of the perforations so that the nail assumes different angular positions successively as it is driven through the perforations in the plates. 75

2. A fastening device for wooden boxes and the like, said device including spaced plates with aligned perforations, and a nail with unevenly spaced rearwardly directed teeth at its side edges, the nail being directed by said edges when passing through the perforations so that it is inclined successively to opposite sides, whereby the withdrawal of the nail in a straight line is impossible by reason of the engagement of 85 the teeth with the edges of the perforations. 80

3. A fastening device for wooden boxes and the like comprising a clip having spaced perforated plates, and a nail having upper and lower series of teeth, the 90 series being separated by a distance that is approximately the same as the distance between the plates, the teeth in each series being separated by a space in excess of the thickness of the plates. 95

4. A fastening device for wooden boxes and the like comprising a clip having spaced perforated plates, and a nail having upper and lower series of teeth, the series being separated by a distance that is approximately the same as the distance between the plates, the teeth in each series being separated by a space in excess of the thickness of the plates, the lower tooth of the upper series and the upper tooth of the 100 lower series being on the same side of the nail. 105

In testimony that we claim the foregoing, we have hereto set our hands, this 10th day of September, 1920.

HERMAN MERKEL.
JACOB BUECHER.
